UNITED STATES PATENT OFFICE

WILLIAM N. THOMAS, OF NEW HAVEN, CONNECTICUT, ASSIGNOR TO SARGENT & COMPANY, OF NEW HAVEN, CONNECTICUT, A CORPORATION OF CONNECTICUT

DESIGN FOR A DOORKNOB OR THE LIKE

Application filed June 25, 1931. Serial No. 40,317. Term of patent 7 years.

To all whom it may concern:

Be it known that I, WILLIAM N. THOMAS, a citizen of the United States, residing in New Haven, in the county of New Haven and State of Connecticut, have invented a new, original, and ornamental Design for Door Knobs or the like, of which the following is a specification when taken in connection with the accompanying drawings, in which:

Fig. 1 is a top plan view of a door knob embodying my design;

Fig. 2 is a side elevational view of the same;

Fig. 3 is a sectional view on line 3—3 of Fig. 1, and

Fig. 4 is a sectional view on line 4—4 of Fig. 3.

It will be observed that the central portion 10 of the upper surface of the knob is of plain unfigured glass entirely transparent, so that the ornament 11, which as shown in Figs. 3 and 4 lies considerably below the surface, may readily be seen when the knob is viewed as shown in Fig. 1.

I claim:

The ornamental design for a door knob or the like substantially as shown and described.

WILLIAM N. THOMAS.
